UNITED STATES PATENT OFFICE.

HARRY LYON, OF BROCKTON, MASSACHUSETTS, ASSIGNOR TO JOHN A. BARBOUR AND PERLEY E. BARBOUR, BOTH OF BROCKTON, MASSACHUSETTS, DOING BUSINESS UNDER THE FIRM-NAME AND STYLE OF BROCKTON RAND COMPANY.

WELT AND METHOD OF MAKING.

1,293,136.

Specification of Letters Patent.

Patented Feb. 4, 1919.

Application filed October 12, 1918. Serial No. 257,875.

To all whom it may concern:

Be it known that I, HARRY LYON, a citizen of the United States, residing at Brockton, in the county of Plymouth and State of 5 Massachusetts, have invented new and useful Improvements in Welts and Methods of Making, of which the following is a specification.

The present invention has reference to 10 welting for use in the manufacture of boots and shoes; and its object is to produce welts which are formed at one edge with a contour adapted to fit closely the space on the bottom of a partly finished shoe in which the welt 15 is laid in the course of manufacture of the shoe, and to accomplish this result in a manner which effects a substantial saving of leather (or other material out of which the welting may be made). Ordinarily welts 20 are made from high grade leather, of which the supply is limited and the cost high, wherefore any material saving in the amount of leather used in producing the welt is important from the standpoints of both 25 conservation of material and reduction of cost. A further and more specific object of this invention is to make duplicate welts, with saving of leather, from a single strip; each welt so made having the characteristics 30 above defined, (of adaptability to fit the welt-receiving space at the shoe bottom), and each one also being so firm and having such mass of material at the edge which fits within such space that, when applied to the 35 shoe with the aid of an inseam-stitching machine according to the usual commercial practice, it will pass through the welt guide of such machine in the required manner and position without crumpling at the edge.

40 I have already invented, and disclosed in an application for Letters Patent of the United States filed by me August 29, 1918, Serial Number 251,886, a method of producing two welts from a strip of leather, or 45 other material, by cutting the strip lengthwise with an angular cut which forms a V-shaped continuous lengthwise rib or salient angle at the edge of one welt, and a complementary V-shaped continuous lengthwise 50 groove or reentrant angle in the edge of the other welt. While that method results in the desired saving of leather, and both the welts produced thereby from the same strip

are successfully operative; yet the welt which has the V-shaped groove in its edge 55 is specifically unlike the other in appearance and is less firm at the edge. In comparison with my said previous invention, the purpose and object of the present invention may be said to be the production from a 60 strip, with equal saving of material, of two welts which are specifically alike and of which each has the fullest necessary degree of firmness at the edge which lies in the angle between the stitch-receiving rib and 65 bottom of the shoe, and of which the co-action with the welt guide of the inseam-stitching machine determines the location of the welt. This object is accomplished by cutting the strip in such wise that each of 70 the two welts derived therefrom has at the dividing edge alternate longitudinally extending V-shaped ribs and grooves or recesses of limited lengthwise extent, which are like but complementary to the grooves or 75 recesses and ribs, respectively, of the other; as more fully explained in the following specification, with reference to the drawings, and particularly pointed out in the claims.

In the drawings which form part of this 80 application,

Figure 1 is a plan view on an enlarged scale of a portion of a strip to be subdivided by cutting according to the present invention into two welts. Figs. 2 and 3 are cross 85 sections on the lines 2—2 and 3—3, respectively, of Fig. 1. Each of these three figures shows the cutting lines on which the strip is divided. Figs. 4 and 5 are perspective views of the resulting welts. Fig. 6 is 90 a cross-section of a lasted shoe bottom, showing my novel welt attached by the inseam to the innersole and upper leather of the shoe.

The same reference characters indicate 95 the same parts in all the figures.

As in my prior application hereinbefore identified, the method starts with the provision of a strip *a* having a width somewhat less than twice the over-all width of each 100 welt required to be made therefrom. This strip is then subdivided, by cuts of proper character, into the welts *b* and *c*. The character of the cuts thus subdividing the strips is shown in Figs. 1, 2 and 3. They may 105 be described as consisting of incisions of

limited length running longitudinally of the strip and extending from the opposite broad faces of the strip and on opposite inclinations from points directly opposite to 5 one another; such incisions being repeatedly alternated with others made on respectively opposite inclinations in contiguous succession throughout the length of the strip. For further explanation of this description reference is made first to the section shown in Fig. 2. Here the incisions referred to are represented as *d* and *e*, the former of which extends on a downward slant to the left 10 from the line *f*, of limited length, in the upper broad face *g* of the strip; and the other of which extends on an upward slant to the left from the under broad face *h* of the strip, which it intersects in a line directly opposite to the line *f* and of equal 15 extent therewith. Both incisions run longitudinally of the strip and are approximately midway between its side edges, so that they cross the longitudinal vertical median plane of the strip. Preferably also the two incisions are on equal although opposite inclinations, which may be an angle of 45°, or a somewhat greater or less angle, whereby 20 there is formed in the edge of the resulting strip *b* a symmetrical V-shaped groove *i*, and in the complementary edge of the welt *c* a symmetrical V-shaped rib *k*.

Next to the incisions thus described, and at each end thereof, other incisions *l* and *m* are made, one pair of which is shown in 25 Fig. 3. These incisions are similar to those designated *d* and *e*, but are oppositely arranged, the incision *l* running downward to the right from the line *n* in the upper face *g* of the strip, and the incision *m* running upward and to the right from a line 30 directly opposite in the under face of the strip. These last named incisions are located approximately midway between the bounding edges of the strip, and preferably 35 are in all respects like the incisions of the first pair except for their respectively opposite directions of inclination. They produce a symmetrical V-shaped rib *o* on the edge of the welt *b* and a complementary symmetrical V-shaped groove *p* in the edge of the welt *c*.

Thus the whole length of the strip is cut by incisions adjoining one another longitudinally, in pairs which are directed alternately oppositely to one another, the end 40 of each pair of incisions adjoining the ends of the next pair. The severance of the welts is completed by cutting transverse incisions *r* between the adjoining ends of longitudinal incisions. When a series of 45 these cuts running the whole length of the strip has been completed, each face of the strip exhibits lines *f*, *f*, *f* of short extent but in alinement, alternating with other lines *n*, *n*, *n* also of short length and in an alinement parallel thereto, and transverse

cuts *r*, *r*, *r*, *r*. Preferably all of the longitudinal lines *f*, *f* and *n*, *n* are equal in length.

The strip is now divided into two parts, which, being separated, form welts having the appearance shown in Figs. 4 and 5. 70 One of these welts as *b* shows in the cut edge grooves *i* and ribs *o* in repeated alternation, while the other welt exhibits at one edge ribs *k* and grooves *p* in repeated alternation, the ribs of each welt being complementary to and matching with the grooves of the other welt. The lips or wings *s* and *t* which flank and bound the grooves in the respective welts are carried out to more or less fine edges and are adapted to be bent 75 toward the central plane of the welt; and when so brought together they are in substantial alinement and in continuation of the ribs *o* and *k*, respectively. They may be thus brought together and secured by adhesive before the welt is put to use, and in that case each finished welt presents a substantially V-shaped rib running its entire length at one edge; but in any event such wings are automatically brought together in the operation of applying the welt 80 to the shoe and stitching the inseam; and after being stitched, the welt has practically the effect of a continuous uninterrupted rib. 85

Without limiting myself to any specific 90 method of forming the cuts hereinbefore described, or any particular machine to be used in making them, I may state that I propose to practise my invention commercially with the aid of a machine having suitable provisions for intermittently feeding the strip which is to be subdivided into two welts as described, and having also chisel-like slitting knives arranged in pairs above and below the pathway of the strip, with 95 operating means therefor; the knives of one pair being arranged to make the cuts such as are herein designated *d* and *e*, and those of the other pair to make the cuts *l* and *m*.

Before being separated into welts as described, the strip may be grooved longitudinally on the flesh side as shown at *w* and *v* in Figs. 2 and 3 and the incisions afterward made between the locations of these grooves. Such grooves serve as channels in which to lay the stitches of the inseam and provide anchoring shoulders for such stitches. These stitch grooves are located at such distances from the cut edges of the welts as to leave enough material for 100 strength; while the original strip *a* is made wide enough to provide the required outward extension of the welt from the groove. 105

Fig. 6 shows in cross section substantially the manner in which a welt made according 110 to this invention is applied to a lasted shoe in the course of manufacture. It may be assumed for the purpose of explanation that the welt so shown is that previously 115 designated as *b*. The discontinuous ribs *o* 120

If the welt fit closely the space in which the edge of the welt is laid, this space being the angle between the shoe bottom and the stitch-receiving rib w of the innersole; the 5 edge part of the shoe upper having been brought into this angle in the lasting operation. y represents the stitches of the inseam, and it will be observed that these stitches pass from the groove w through the full 10 thickness of the welt at the base of the rib o , whereby it is apparent that the formation of the welt in the manner described does not weaken it in the least. Each of the short discontinuous ribs of the welt occupy the 15 position here indicated, while those lips s of the alternating grooves which come next to the upper are bent to conform to the welt-receiving angle of the shoe bottom, whereby the stitches of the inseam pass 20 through them also, and they also furnish material to give a secure anchorage for the stitches in the welt. The outer lips of the same grooves will be bent down against the inner lips in the operation of the stitching 25 machine, and add strength to the stitch anchorage. If subsequently these outer lips should spring outward, their extreme edges might be trimmed off in the subsequent inseam trimming operation, but if so the 30 amount of leather converted into waste by that means would be an inconsiderable fraction of the saving effected by the invention.

The amount of saving which is effected according to my present invention is exactly 35 the same as explained in my prior application before referred to, and consists in the difference between the width of the strip a shown in Fig. 1, and the sum of the over-all widths of the two welts which are cut there- 40 from, such over-all widths being measured from the tip of the V-shaped rib at one edge of the welt to the opposite square edge. The inner edge of the welt, by which I mean the edge formed by the subdividing cut, is 45 given such firmness by means of the frequent ribs o (or correspondingly k) that it correctly guides the welt in being applied by the aid of the welt guide of the inseam stitching machine. That is, such ribs have 50 greater strength and firmness than the thinner separated lips s (or correspondingly t), so that the ribs overcome any tendency which might exist for the softer and thinner lips to crumple and curl up against the 55 welt guide; while the frequency of the ribs and the shortness of the spaces between them causes at least one rib always to be in co- 60 action with the guide. Of course as the outer edge of the welt is square, no trimming of that edge is necessary, except at those parts of the shoe where the extension of the sole

is required to be trimmed down to a narrow width.

What I claim and desire to secure by Letters Patent is:

1. A welt having on one edge longitudinally extending alined V-shaped ribs and grooves of limited extent in repeated alternation.

2. A welt having on one edge longitudinally extending alined V-shaped ribs and grooves of limited extent in repeated alternation, said grooves being bounded by lips which are adapted to be bent toward one another substantially into the planes of the faces of the adjacent ribs.

3. A welt having on one edge a series of discontinuous V-shaped ribs, the apices of which are in alinement with one another approximately midway between the extended planes of the opposite faces of the welt, and V-shaped grooves intermediate and alternating with said ribs having alined vertices substantially midway between said faces and back of the line of said apices.

4. A welt having on one edge a series of discontinuous V-shaped ribs, the apices of which are in alinement with one another approximately midway between the extended planes of the opposite faces of the welt, and V-shaped grooves intermediate and alternating with said ribs having alined vertices substantially midway between said faces and back of the line of said apices; the sides of said ribs and grooves being respectively on approximately equal, but opposite inclinations.

5. The method of producing complementary welts which comprises cutting in a strip of suitable material incisions of limited longitudinal extent which extend from opposite locations in opposite faces of the strip and on opposite inclinations to an intersection in the body of the strip, and forming adjacent to the ends of each pair of incisions so made, similar but oppositely inclined incisions.

6. The method of producing complementary welts which consists in cutting in a strip of suitable material incisions of limited longitudinal extent which extend from opposite locations in opposite faces of the strip and on opposite inclinations to an intersection in the body of the strip, and forming adjacent to the ends of each pair of incisions so made, similar but oppositely inclined incisions, and cutting also transverse incisions which intersect the adjoining ends of successive pairs of inclined incisions.

In testimony whereof I have affixed my signature.

HARRY LYON.
